BOTTLE

Richard L. Platte, Ann Arbor, Mich., assignor to Hoover
Ball and Bearing Company, Saline, Mich.

Filed July 8, 1964, Ser. No. 80,765

Term of patent 14 years

(Cl. D58—6)

FIG. 1

FIG. 2

FIG. 4

FIG. 3

FIG. 5

FIG. 6

The rear and side not shown are substantially the same as the front and side shown.

The dominant features of my design reside in the portions shown in full lines.

I claim:

The ornamental design for a bottle, as shown and described.
